UNITED STATES PATENT OFFICE

MERLE B. BARTON, OF PEORIA, ILLINOIS.

AUTOMOBILE CURTAIN-SUPPORT.

1,017,643.

Specification of Letters Patent.

Patented Feb. 20, 1912.

Application filed December 27, 1910. Serial No. 599,442.

To all whom it may concern:

Be it known that I, MERLE B. BARTON, a citizen of the United States, residing at Peoria, in the county of Peoria and State of Illinois, have invented, certain new and useful Improvements in Automobile Curtain-Supports; and I do hereby declare that the following is a full, clear, and exact description of the invention, which will enable others skilled in the art to which it appertains to make and use the same.

This invention relates to covering tops for vehicles and pertains more particularly to a side curtain in conjunction therewith for the door of an automobile.

The object of the invention is to provide a curtain for the door of a vehicle that can be easily attached and detached all of which will be readily understood from the accompanying drawing in which,

Figure 1 is a side elevation of an automobile showing my attachment. Fig. 2 shows the inner side of an automobile door in perspective. Fig. 3 is an elevation 25 of the inner side of a curtain for the door showing a frame on which it is carried. Fig. 4 is a plan of a portion of the curtain shown in Fig. 3. Fig. 5 shows the curtain in perspective. Fig. 6 is an elevation of the inner side of the curtain and shows an elevation of a modified form of carrying frame.

The door of the vehicle is indicated in Fig. 1 by the letter A, the canopy or top of the vehicle together with its side curtains by B, and the curtain attachment for the door by C and in Fig. 6 the curtain is indicated by C' which I usually construct separate from the top B, although, of course, it could constitute a part of the latter at the hinge side of the door. There are several methods which may be resorted to for holding the curtain a few of which I have shown.

In Fig. 1, for example, a U-shaped frame is illustrated at D in broken lines. The lower free extremities of the upright portions of this frame may be secured on the door in any good manner but preferably in such a manner that it can be readily attached and detached without the removal of nuts or bolts. For example, I may place either on the inner or outer side of the door a pair of socket-members E into which the said extremities of the frame may be in-

serted as shown in Fig. 2 and there held, if desired, by means of thumb screws F, although the latter may not be used.

I have shown in Fig. 3 the same structure illustrated in Fig. 1 the inner side of the curtain, however, being brought to view, 60 said curtain being further illustrated in perspective in Fig. 5. At each vertical edge it is provided with a loop G created for example, by turning over the edge of the material and sewing or otherwise attaching the 65 said edge to the body of the curtain in the position indicated in Fig. 4 in plan so that said curtain may be slidable upon the frame.

The top portion of the curtain extends above these loops and to this said portion 70 hooks H, for example, may be attached to hook on the top portion of the frame D described. With this structure the frame may be slipped into the loops, the hooks being used to hold the curtain in place, the 75 said curtain being made of the proper width so as to be stretched upon the frame whereby it will lie flat and smooth.

In Fig. 6 I illustrate substantially the same form of frame but it has the advantage 80 that it may be folded into a compact form so as to be stored away under a seat. It consists of upright members J to the upper end of each of which is pivotally attached one end of an arm K; the opposite ends of the 85 said arms being pivotally connected as indicated at L. In this form one edge of the curtain may be sewed at M along one of the said uprights J and may be slidable thereon, while its opposite edge as well as its top 90 edge, may be hooked upon the upright J and arms K respectively by means of hooks N corresponding to the hooks H in Figs. 3 and 5. In adapting this form of curtain for storing it away it is only necessary to 95 swing the arms K on the pivot L and bring the uprights J toward one another as illustrated in broken lines after unfastening the hooks N. The arms and the uprights can thus be brought into very close relation, the 100 curtain being wrapped about them and without danger of breaking the celluloid window usually employed. However, said arms K may be replaced by a single member or curtain support such as P in Fig. 7, for example, in which event its ends are pivoted to the members J so that the three parts will 105 fold and lie parallel to one another, the cur-

tain being removed to permit such parts to be brought into parallelism.

I provide a support for the door curtain which may be quickly removed from the door without great effort and may be stored away this being especially easily accomplished by reason of the fact that said curtain is not a part of the vehicle top B. I may, of course, use any means for attaching the curtain frame to the door, but as already stated it is my preference to use one that can be slipped into position and held by friction.

I may not connect the two upright members of the forms shown in Figs. 1, 3, and 6 by the members D, K, P in which case the curtain may be attached permanently to the said uprights and when removed from the door the entire device may be readily made into a roll to be stored away. The folding types of curtain holder herein by having

their parts collapsible occupy but a very small place when stored away in the vehicle.

Having described my invention I claim:

In combination with a vehicle door, a collapsible curtain holding frame consisting of two uprights, a separate member pivoted at one end to the upper end of each of said uprights, said members being pivotally connected at their free ends, means for detachably securing the frame to the door, and a curtain secured at one of its edges to one of the uprights, and means at its opposite edge to detachably secure that edge to the opposite upright.

In testimony whereof I affix my signature, in presence of two witnesses.

MERLE B. BARTON.
